UNITED STATES PATENT OFFICE.

THOMAS FURLONG, OF ST. LOUIS, MISSOURI.

DESIGN FOR A SHIELD FOR BICYCLE-TIRES.

SPECIFICATION forming part of Design No. 25,459, dated May 5, 1896.

Application filed April 6, 1896. Serial No. 586,453. Term of patent 14 years.

To all whom it may concern:

Be it known that I, THOMAS FURLONG, a citizen of the United States, residing at the city of St. Louis, State of Missouri, have invented a certain new and original Design in Shields for Bicycle-Tires, of which the following is a full, clear, and exact description, reference being had to the accompanying drawings, forming a part of this specification, 20 wherein—

Figure 1 is a side elevational view of my new and original design in tire-shields. Fig. 2 is an end elevational view of the same, showing at the upper side thereof the shield in cross-section. Fig. 3 is an enlarged cross-sectional view of the shield, and Fig. 4 is an enlarged plan view of the face of the same. 15

This invention relates to a new and original design in shields for bicycle-tires; and it 20 consists, generally stated, in the shape and ornamentation of the same, as will hereinafter be described and claimed.

The body of the shield A is semicircular in shape, the inner side edges of which are ornamented by a bead *a*, which extends entirely 25 around the shield. The periphery of the shield is formed by a compound curve, which terminates at the edges of a flat thread B. This thread B is ornamented with a number of checker-like projections, which terminate 30 in points, as shown in Fig. 3.

Having thus described my new and original design in tire-shields, what I claim, and desire to secure by Letters Patent of the United States, is— 35

The design for tire-shields, substantially as herein shown and described.

In testimony whereof I hereunto affix my signature, in presence of two witnesses, this 4th day of April, 1896.

THOMAS FURLONG.
